UNITED STATES PATENT OFFICE.

ANSON O. KITTREDGE, OF NEW YORK, N. Y., ASSIGNOR TO THE ACCOUNT, AUDIT AND ASSURANCE COMPANY, OF NEW JERSEY.

SUMMARY JOURNALIZING-LEDGER.

SPECIFICATION forming part of Letters Patent No. 650,605, dated May 29, 1900.

Application filed November 22, 1897. Serial No. 659,389. (No model.)

To all whom it may concern:

Be it known that I, ANSON O. KITTREDGE, a citizen of the United States, residing at New York, in the county and State of New York, have invented a Summary Journalizing-Ledger; and I hereby declare that the following is a full, clear, and exact description of the same.

This invention relates, primarily, to that class of account-books called "summary-ledgers," in which a statement of the business is from time to time summarized or reduced to its lowest terms to exhibit a synoptic view of the various accounts. Such summarizing has been heretofore effected by posting from the regular books of the business upon any given date to accounts in the summary-ledger; but no provision has heretofore been made within the ledger itself to indicate and effect the cross-entries that are necessary to procure or exhibit a balance-sheet of the business.

The present invention furnishes an improved construction for a ledger in which after the opening-balances of the several accounts are entered the ledger may not only present at any given later date a synopsis of all the transactions of the business up to that date, but may also, without using a separate journal, afford means for indicating and effecting cross-entries between the various accounts, so as to express the disposition of profits and losses and the consequent modification of the capitalistic accounts, such as dividends and divisions or impairment and surplus. These functions are performed in a single book by providing one of the pages of the book, preferably in advance of the regular accounts, with a date-column and a journalizing column or columns, with lines extended transversely through these auxiliary columns and those of the succeeding accounts, so as to locate entries of a given date in any of the accounts upon the same line.

The invention is practiced most readily by providing a group of narrow leaves with spaces to receive the several accounts and arranging a wider leaf at one end of the group, upon the projecting margin of which a date-column and a column for journalizing for mulæ can be exposed to view, together with any of the accounts upon the narrower leaves.

To extend the use of the invention, the

book is preferably formed in sections, each having a group of the narrow leaves sufficient to receive all of the necessary accounts and each having a wider leaf with the journalizing-column upon its margin for use in connection with such section. The lines which are extended transversely through all of the columns are correspondingly numbered from the top to the bottom of each page upon the narrow leaves and upon the exposed margin of the wider leaf. By providing the date and journalizing columns upon the exposed margin of such wide leaf it may be used in connection with the several narrower leaves as they are successively turned over upon the wide leaf, the transverse lines across the date and journalizing columns and account-columns enabling the entries upon a common date to be readily located in the various accounts. That portion of the wider leaf which is covered by the narrower leaves as they are turned over furnishes room for a column of journalizing particulars, wherein are entered the explanations of the various entries in the column of formulæ. The two journalizing-columns furnish a means of specifying in the "formulae-column" the accounts between which cross-entries or transfers are made and in the column of particulars the purpose for which such cross-entries are made. The cross-entries permit the closing or modifying of the several accounts, so that new footings are exhibited which show with perfect exactness the condition of business at the date of posting.

The invention will be understood by reference to the annexed drawings, in which—

Figure 1 is a view of the first two pages and the projecting margin of the last page of the first section of the ledger. Fig. 2 is a view of the third and fourth pages and part of the first and last pages of the same section. Fig. 3 is a similar view of pages 5 and 6. Fig. 4 is a similar view of pages 7 and 8. Fig. 5 is a similar view of pages 9 and 10. Fig. 6 is a similar view of pages 11 and 12, and Fig. 7 is a view of the last two pages and the projecting margin of the first page of such section. Fig. 8 is a perspective view of the summarizing-ledger.

The ledger shown herein is formed with a plurality of sections, each consisting of a plurality of the narrow leaves and a single wider

leaf at the beginning of the section. The pages of each section are in the illustrations divided into vertical spaces for receiving certain general classes of accounts, with subdivisions or subspaces to receive accounts representing subclasses of the general classes. In practice each section contains all of the accounts of a certain business and is adapted by reason of its journalizing-column to receive all the original and cross entries required in a given period of time, as one week, one month, or more, to form a statement of the business during such period. The term during which each section could be used would depend upon the number of lines occupied by the entries. If each sufficed for the transactions for one week, the book would require fifty-two sections to exhibit the business for a year, or twelve sections if each section would hold the transactions for one month.

Figs. 1 to 7, inclusive, show the pages of a single section adapted for a certain business, and Fig. 8 shows the book open at the last page of one of the sections, which page is represented in Fig. 7.

The successive entries in the journalizing-columns would be made upon successive lines, but are widely separated in the example illustrated to prevent crowding upon the drawings.

Upon the projecting margin of page 1 of the section is placed the vertical date-column A, headed "Date," the vertical journalizing-column B, headed "Formulae," and the vertical guide-number column C, headed "No." The remainder of the page, which is covered by the narrow leaves when turned over, is employed for a column D, headed "Explanations and Particulars." The columns A, B, C, and D are transversely divided by lines E, extending horizontally across page 1 and continued through the remaining pages of the section in order that the entries can be read from left to right. The small horizontal spaces formed by the lines E are numbered, consecutively, from "0" in the number-column C downwardly, and each page or general division of the section is provided with a similar guide-number column with similar numbers, which guide the eye in locating entries upon a uniform date or line in all of the accounts. Thus at the left and right hand edges of page 2, Fig. 1, are number-columns, (designated F and H,) between which is a space for a general division G, headed "Accounts with cash," under which heading are columns (designated g g' g'') headed, respectively, "Drawer and safe," "Bank," and "Total cash balance."

Pages 3, 4, and 5, Figs. 2 and 3, are shown provided with several number-columns I, between which are spaces for a general division J, headed "Accounts with merchandise," such space having subdivisions J' J'' J³, headed, respectively, "Manufacturing," "Buying," and "Selling."

Pages 6 and 7, Figs. 3 and 4, are shown provided with spaces K for a general division

headed "Accounts with debtors," such space having subdivisions K' K'' K³, headed "Installment ledger," "Sundry debtors," and "Notes receivable."

Page 8, Fig. 4, is shown provided with a space L for a general division headed "Accounts with investments," such space having subdivisions L' L'' L³, headed "Necessary," "Speculative," and "Total balance of investments."

Pages 9 and 10, Fig. 5, are shown provided with spaces L⁴ for a general division headed "Accounts with creditors," such space having subdivisions l l' l'' l³, headed "Purchase accounts," "Sundry creditors," "Notes payable," and "Total balance of creditors."

Page 11, Fig. 6, is shown provided with a space M for a general division headed "Reserve funds," such space having subdivisions m m', headed "For investment accounts" and "For debtors accounts."

Page 12, Fig. 6, is shown provided with a space N for a general division headed "Results of transactions," such space having subdivisions n n', headed "Expense accounts" and "Losses and gains."

Page 13, Fig. 7, is shown provided with a space O for a general division headed "Disposition of profits and losses," such space having subdivisions o o', headed "Dividends and divisions" and "Impairment and surplus."

Page 14, Fig. 7, exhibits the last leaf of the section and is shown provided with three spaces P Q R, headed "Capital," "Proof-columns," "Cost of goods sold," and its margin provided with a space S, headed "Remarks."

In Figs. 2 to 7, inclusive, the margin of page 1 upon the broad leaf at the beginning of the section is shown projecting at the left side of the shorter leaves, while Fig. 1 shows the whole of page 1, with the entries which in the other figures are covered by the short leaves. Fig. 7 shows the whole of page 14 at the last end of the section, the margin only of which (the space S) appears in the preceding figures, and this page 14 represents the front side of the broad leaf at the beginning of the succeeding section. The chief novelty in the construction is the provision of journalizing-columns for use in connection with the ledger-entries, and such columns are used as follows: The balances of the several accounts at the opening of the ledger are entered in the several spaces provided for such accounts, the drawing showing the balances entered, under date of April 10, 1897, all upon the line designated by the O in the several number-columns, the word "Balances" being entered in the journalizing-column B, headed "Formulae," and the explanation "As per balance-sheet of this date" being entered in the journalizing-column D, headed "Explanations and particulars." Under date of April 17 a summary of debit and credit footings from the several auxiliary books of the business is shown entered in the various accounts upon line designated number 6, the word "Report"

125
130

being placed in the first journalizing-column B and the explanation "Bookkeeps summary of transactions" in the column D.

To express the disposition of profits and losses, cross-entries are made with the use of the journalizing-columns, as follows: The selling account is debited with "\$699.92," the cost of the goods sold, (per space R, page 14, Fig. 7,) by a transfer of "\$699.92" from the selling account, page 5, Fig. 3, to the buying account, page 4, Fig. 2, by entering the words "Selling to buying" in the formulæ-column B, and the explanation "For goods sold to date at cost prices" in the second journalizing-column D. The balance in the selling account represents the gross profits for the period, which is transferred to loss and gain account by the second journal-entry on page 1, where on line 17 the words "Selling to loss and gain" are entered in column B and the explanation "For gross profits on goods sold" in column D. The loss and gain account is then debited with the balance in the expense account representing the expenses of the business in the same period and the same credited to expense account, which closes the latter, the journal-entries being on line 23, page 1, "Loss and gain to expense" in column B, and the explanation "For expenses of business to date" in column D. The balance of loss and gain account "\$372.45" is then transferred to "Dividends and divisions" account, page 13, Fig. 7, the journal-entries being on line 29, page 1, "Loss and gain to dividends" in column B and the explanation "For net profits to date" in column D. The balance in dividends and divisions is then transferred to "Impairment and surplus" account, page 13, Fig. 7, the journal-entries on line 34, page 1, being "Dividends to imps. and sur." in column B, the explanation "For profits carried to surplus" in column D. The word "Footings" is shown in line 37, column B, and the explanation "Accounts that are closed" in column D, and the footing-lines drawn under such accounts show that they are closed. The amounts remaining in the unbalanced accounts stand as they are to be added in with the footings of the succeeding period. Proof-columns (shown in page 14, Fig. 7) permit the comparison of the debit and credit postings the same as in an ordinary trial-balance.

Whenever the journalizing steps above described are completed, the ledger presents a summary of the transactions of the business to date and a statement of the solvency of the business at that date. A great advantage is secured by having the journalizing-column in the ledger itself, as it greatly facilitates the formation of cross-entries in the ledger, while it obviates the necessity of using a separate journal, and thus renders the accounts more private and more compact.

The advantages of my invention are very great, as by it the business man is enabled to know his condition of solvency at any

time without the preliminary work of drawing off a statement, and, further, to make the necessary cross-postings in the ledger by journal-entries in the same book, so as to learn exactly the amount of profit or loss to date. Very important results therefore are accomplished by the one book, which is the general ledger of the business, that are impossible without it, save by the examination of several books, with the final showing in a form entirely outside of the regular books, as on a detached sheet of paper or a leaf in a book devoted to the record of prepared statements.

Having thus set forth the nature of the invention, what is claimed herein is—

1. As a new article of manufacture, a summary journalizing-ledger, comprising a series of adjacent vertical account-spaces each having columns headed respectively "Dr." and "Cr." a vertical journalizing-column at the side of the series with a heading indicating the journalized accounts, and lines extended transversely through all of the spaces and columns, the whole arranged and operated as set forth to effect cross-entries between the several accounts at a given date, substantially as herein set forth.

2. As a new article of manufacture, a summary journalizing-ledger having a series of narrow leaves bearing adjacent vertical account-spaces each having columns headed respectively "Dr." and "Cr." and a broader leaf at the front of the series having upon the projecting margin a vertical journalizing-column with a heading indicating the journalized accounts, and lines extended transversely through all of the spaces and columns, the whole arranged and operated as set forth to effect cross-entries between the several accounts at a given date, substantially as herein set forth.

3. As a new article of manufacture, a summary journalizing-ledger, comprising a series of adjacent vertical account-columns each adapted for debit and credit postings and having at one side a date-column and a vertical journalizing-column with divisions for formulæ and particulars respectively, with lines extended transversely through all of the columns, to receive postings of uniform date upon the same line whereby cross-entries between the several accounts are indicated and explained, substantially as herein set forth.

4. As a new article of manufacture, a summary journalizing-ledger having a series of narrow leaves bearing adjacent vertical account-columns adapted each for debit and credit postings, and a broader leaf at the front of the series having upon the projecting margin vertical columns for dates and formulæ, and upon the inner portion of such wide leaf an explanatory-column for the journal-entries with lines extended transversely through all of the columns to locate postings of uniform date in all of the account-columns, substantially as herein set forth.

5. As a new article of manufacture, a sum-

mary journalizing-ledger having a series of narrow leaves each bearing a guide-number column, and such narrow leaves having spaces for general divisions of accounts with several account-columns in each space for specific divisional accounts, and a broader leaf at one end of the series having upon the projecting margin vertical columns for dates, formulæ,

and guide-numbers, substantially as herein set forth. 10
